(57) **CLAIM**

The ornamental design for equipment for reproduction of sound, as shown and described.

DESCRIPTION

FIG. 1 is a front perspective view of equipment for reproduction of sound showing our new design;

FIG. 2 is a right side elevational view showing the design for the equipment for reproduction of sound of FIG. 1;

FIG. 3 is a left side elevational view showing the design for the equipment for reproduction of sound of FIG. 1;

FIG. 4 is a rear elevational view showing the design for the equipment for reproduction of sound of FIG. 1;

FIG. 5 is a front elevational view showing the design for the equipment for reproduction of sound of FIG. 1;

FIG. 6 is a top plan view showing the design for the equipment for reproduction of sound of FIG. 1; and,

FIG. 7 is a bottom plan view showing the design for the equipment for reproduction of sound of FIG. 1.

The broken lines shown in the drawings illustrate portions of the equipment for reproduction of sound that form no part of the claimed design.
